MACHINE FOR OPERATING ON SHOE SOLES

Gustave Frost, Long Beach, N. Y., assignor to
Andrew Geller, Inc., Brooklyn, N. Y., a corpora-
tion of New York

Application September 7, 1949, Serial No. 114,327

6 Claims. (Cl. 12—40)

1

This invention relates to a machine for operating on shoe parts and relates more particularly to a machine for cutting slots or openings of special contour in the heel section of an inner sole for a lady's shoe.

In recent years it has been the fashion in certain types of shoes to employ two straps to form the quarter of the shoe rather than to provide a full heel-enclosing quarter. This arrangement permits the rear portion of the heel of the wearer to be fully exposed, the two straps extending upwardly from the sides of heel section. The lower terminals of the straps are suitably secured between the inner sole and the outer sole and the straps thus overlie a portion of the edges of the inner sole as they extend upwardly over the ankle.

A more comfortable shoe, and one which is more attractive in appearance is formed by cutting curved slots on opposite sides of the heel section of the inner sole, such slots being substantially equally spaced throughout their lengths from the opposed edges of the heel section, which edges are themselves somewhat curved. Thus, the straps which form the quarter, instead of extending over the edges of the inner sole, pass through the slots and are suitably anchored between the inner sole and outer sole.

These slots must not be vertical but must be diagonally inclined downwardly and inwardly so that the straps, as they emerge from the slots assume a curved contour to closely hug the curved sides of the heel of the wearer. Prior to the present invention these slots had to be cut by hand which was a difficult and tedious process and which was made more difficult by virtue of the fact that the slots had to have a width substantially equal to the thickness of the straps, so two cuts had to be made for each slot so as to give this width. Moreover, many inner soles were ruined during the process.

It will thus be apparent that an important object of the present invention is to provide a machine which will quickly and accurately cut a slot having necessary width and of the aforesaid contour, which contour may be described as a section of the surface of a cone.

In accordance with the present invention a small power driven circular saw is employed for the cutting operation, such cutting, however, being performed while the heel section is laterally deformed by holding it between two curved vise-like surfaces shaped complementary to each other. While so held against movement, the saw is moved against the inside and cuts there-

2

through over a sufficient arc to permit the strap to pass through the slot. The saw is of sufficient thickness to cut a slot of suitable width.

In the drawings:

Fig. 1 is a plan view of a machine embodying the present invention, a part of the housing being broken away to show the circular saw.

Fig. 2 is a front elevation of the machine.

Fig. 3 is a vertical section taken on line 3—3 of Fig. 2.

Fig. 4 is a horizontal section taken on line 4—4 of Fig. 2.

Fig. 5 is a broken section taken on line 5—5 of Fig. 2.

Fig. 6 is a perspective view of the inner sole and quarter assembly with the slots cut for the straps comprising the latter, by the machine of the present invention.

Fig. 7 is a broken section through the heel section of the shoe and showing the relation of the insole and straps with the heel of the wearer.

Fig. 8 is a broken section taken through a modified form of the invention provided with dual cutting assemblies.

Fig. 9 is an insole "S" is shown in Fig. 6, the heel section thereof having a rear curved edge 2 and opposed curved side edges 3. The quarter which embraces opposite sides of the heel of the wearer is composed of two straps 4 and 5 which are joined at a point above the inner sole by a short strap 6. Straps 4 and 5 may be provided with suitable fastening means such as buckles (not shown) to be secured around the front of the ankle. Instead of causing the straps to overlie portions of opposed side edges 3 the straps pass through curved slots 7 and 8 and such slots are diagonal in transverse section, i. e., their upper edges are closer to edges 3 than their lower edges.

The heel of the wearer is shown in Fig. 7 at 9 and the straps closely engage the wearer's heel at the sides which would not be the case if the slots were vertical.

The operating parts of the machine which cut these through slots are mounted on a table 10 which is supported by legs 11 at the corner sections. The base table is formed with an elongated opening 12 to accommodate a movable bearing assembly 13 associated with a motor 14.

The motor is rigidly mounted at the lower end of the bearing assembly and the motor shaft 15 passes upwardly through such bearing.

The bearing is supported in a bushing 16 carried by an arm 17 which is hinged at one end 55 thereof on a pivot pin 21 carried by a bracket 22

rigidly supported on the base plate. Such a hinge assembly is conventional.

The arm is provided with a handle 23 at its opposite end for the purpose of moving it manually forwardly. A spring 24 is employed for returning the arm to starting position. A bracket 25 carried by the arm adjacent the handle forms a journal or a fixed support for a pin 26 on which is mounted a roller 27 which traverses the table top during forward and rearward movement of the arm to reduce the bending stress on pivot pin 21. A set screw 31 mounted in a block 32 provides an adjustable stop to limit forward movement of the arm. A bracket 33 having a foot 34 is arranged to travel with the set screw 15 while the foot is in sliding contact with the base plate which at this point is provided with graduations 35 to serve as a guide to move the set screw to an adjusted, fixed position. Pins 36 on opposite sides of the bracket produce conjoint movement of the bracket and set screw as the latter is rotated.

A circular saw 37 is rigidly mounted at the upper end of the motor shaft, the saw being of sufficient thickness to cut a slot of desired width.

A sole supporting plate 40 is mounted diagonally with reference to table top 10 and is affixed to the inclined upper edges 41 of spaced vertical frame members 42 rigidly mounted in spaced relation on the upper surface of the table top at its forward edge. This sole-supporting plate is illustrated as being disposed at an angle of about 45° to the plane of rotation of the cutting element but it will be understood that this is suggestive only and that the angle may vary depending upon the particular construction of the shoe. The angle between the cut and the upper surface of the sole should always be less than a right angle, however.

The central portion of the plate 40 is formed with a concavely curved cavity 43 shown particularly in Fig. 5. The heel section 4 of the inner sole is forced to assume the contour of said cavity during the operation by means of a concavely curved presser plate 46 shaped complementary to such cavity. Plate 46 is mounted at the rear end of a vertical, generally triangular support 51 which is rigidly secured to a horizontal slide 52 mounted for reciprocating travel in spaced trackways 53. These trackways are secured by screws 54 to a horizontal fixed plate 55 which is secured to vertical frame members 42.

Slide 52 is moved rearwardly carrying with it presser plate 46, by a lever 56 pivoted at 57 on plate 55 and having an inclined cam surface 58 and a surface 59 concentric with the axis. A spring 62 returns slide 52 to its starting position, such spring being mounted in a cylindrical housing 63 associated with plate 55. The upper edge of the diagonal sole-supporting plate 40 is fitted with a guard 64 having downwardly depending ears 65 secured to the plate.

For the purpose of properly positioning the sole before it is held between presser plate 46 and cavity 43 L-shaped members 66 and 67 formed with slots 68 are mounted for reciprocating travel on plate 40 by headed pins 69. The guide members are moved to an adjusted, fixed position by a T-shaped lever 73 pivoted at 74 and connected at 75 to the guide members. The free end of the lever is fitted with a pointer 76. A supplemental plate 77 is mounted in spaced relation to plate 40 and has size numbers printed thereon. When the lever is moved to a desired position it is secured there by a set screw 80.

A housing 81 may enclose the cutter assembly, and a plate 82 carried thereby may serve to limit upward movement of the sole "S."

The operation of the machine is as follows:

The inner sole "S" is placed upon plate 40 with its rear curved edge 2 in contact with guide 68 and the lever 56 then rotated above 100° until the concentric surface 59 contacts the forward edge of slide 52 to lock the slide in place. Pressure plate 46 has now securely clamped the heel section of the sole in its laterally deformed position and handle 23 on the cutter head assembly is moved forwardly, causing the saw to cut the slot. The farther the saw travels the longer the slot. Accordingly, before the operation commences, set screw 31 has been adjusted for a slot of proper length for the width of the strap. The handle is released and spring 24 returns the cutter assembly to starting position.

The sole is now released by manipulation of lever 56 and the sole reversed to cause the heel to contact the other guide member 67 and the operation repeated.

It was earlier pointed out that the angle between the plane of rotation of the cutting element and the plane of the sole-support may vary but that the angle between the slot and the upper surface of the sole should be less than a right angle. Accordingly, when reference is made in the appended claims to "less than a right angle" it is deemed to refer to the angle between such plane of rotation and the front or upper surface of the supporting plate.

In the modified arrangement of Fig. 8, two saws 70 and 71 are employed each being secured to shafts 72 and 73 respectively, disposed at right angles to each other. The sole supporting plate 74 has the cavity 75, the central vertical section line of the cavity being shown at 76. No particular means for rotating the shafts nor for moving them toward the work are illustrated and no pressure member for securing the sole in the cavity in laterally deformed relation is illustrated. By this arrangement, both cuts can be made simultaneously.

While two forms or embodiments of the invention have been shown and described herein for illustrative purposes, and the construction and arrangement incidental to specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

What I claim is:

1. A machine for cutting arcuate slots in articles and comprising a frame; an article-supporting plate mounted on the frame and having a cavity for receiving a portion of the article, a movable presser plate having a surface complementary to such cavity and arranged to hold the article in the cavity in deformed relation during the cutting operation, a cutter assembly including a motor provided with a shaft and a revolvable linear cutting element secured to the shaft, the axis of the shaft being disposed at less than a right angle to the plane of the article supporting plate and the article secured thereon, means for moving the cutter assembly toward and away from the plate and means for limiting the entry of said linear-cutting element into said article.

2. A machine of the character described and comprising a frame, an arm pivotally mounted at one end thereof on the frame on a vertical axis, a cutter assembly carried by the arm and comprising a revoluble cutter having a linear cutting stroke and a motor for driving the cutter, a support for an article to be cut rigidly mounted at the front of the frame and being inclined rearwardly from the vertical, said support having a concavely curved cavity therein to receive the article in deformed relation during the cutting operation, and a movable presser plate arranged to securely hold the article in deformed relation in such cavity while said cutter linearly cuts an angular slot therein, and said slot assuming an arcuate relationship upon the release of said presser plate.

3. A machine for cutting arcuate slots in shoe soles comprising a frame, a sole-supporting plate mounted on the frame and having a cavity for receiving a portion of the sole, a movable presser plate having a surface complementary to such cavity and arranged to hold the sole in the cavity in deformed relation, a movable cutter assembly including a motor provided with a shaft and a linear cutting element secured to the shaft, the axis of the shaft being disposed at substantially a 45° angle relative to the plane of the plate, and presettable means for limiting the movement of the cutter assembly toward and away from the plate thus regulating the length of the deformed linear-cut slot.

4. A machine for cutting arcuate heel slots in inner soles comprising a frame, a sole-supporting plate mounted on the frame and having a cavity for receiving the heel section of the sole, a movable presser plate having a surface complementary to such cavity and arranged to hold the heel section in the cavity in laterally deformed relation during the cutting operation, a cutter assembly including a motor provided with a shaft and a linear cutting element secured to the shaft, the axis of the shaft being disposed at an angle of less than a right angle to the plane of the plate, and means for moving the cutter assembly toward and away from the plate to effectively cut a linear slot during the deformed holding of said article.

5. A machine for cutting arcuate heel slots

in inner soles comprising a frame, a sole-supporting plate mounted in the frame and having a concavely curved cavity for receiving the heel section of the sole, a movable presser plate having a surface complementary to such cavity and arranged to hold the heel section in the cavity in laterally deformed relation during the slot cutting operation, a cutter assembly including a motor provided with a shaft and a linear-cutting circular saw secured to the shaft, the axis of the shaft being disposed at an angle of substantially 45° to the plane of the plate, and pivotal means for moving the cutter assembly toward and away from the plate.

6. A machine for cutting arcuate heel slots in inner soles comprising a frame, an arm pivotally mounted at one end thereof on the frame on a vertical axis, a cutter assembly carried by the arm intermediate its ends and including a linear-cutting circular saw and a motor for driving the saw, a sole-support rigidly mounted at the front of the frame and being inclined at its upper end rearwardly from the vertical, the plate having a concavely curved cavity therein to receive the heel section of the sole in laterally deformed relation, and a manually movable presser plate for holding the heel section in such cavity in deformed relation to enable said linear-cutting saw to effectively cut an arcuate slot in said heel section.

GUSTAVE FROST.
